[57] CLAIM

The ornamental design for a dental set for dental materials, as shown and described.

DESCRIPTION

FIG. 1 is a top left front perspective view of a dental set for dental materials, showing my new design and shown with the cover opened;

FIG. 2 is a front view of the new design with the cover opened;

FIG. 3 is a front view similar to FIG. 2, viewed from somewhat further up, with the cover omitted;

FIG. 4 is a representation similar to FIG. 3, the left one of the fittings arranged in the set being swivelled upwards into an inclined position;

FIG. 5 is a view of the new design similar to FIG. 1, without cover;

FIG. 6 is a perspective front view from the upper right side of the new design with the cover omitted;

FIG. 7 is a view of the new design with the cover omitted, seen from the upper right side;

FIG. 8 is a view of the new design with the cover omitted, seen from the upper left side;

FIG. 9 is a view of the new design with the cover closed, viewed from the front and above;

FIG. 10 is a representation of the new design with the cover closed, viewed from the upper left side;

FIG. 11 is a representation of the new design with the cover closed, viewed from the upper right side;

FIG. 12 is a top plan view of the new design;

FIG. 13 is a view of the new design with the cover closed, seen from the upper rear side;

FIG. 14 is a perspective view showing the fitting of the new design without the casing in a front angle view, from the upper right side;

FIG. 15 is a perspective view of the fitting of the new design in a front angle view, from the upper left side;

FIG. 16 is a front view from an elevated point of the fitting of the new design;

FIG. 17 is a front view from an elevated point of the fitting in its backwardly inclined position.
